CLAIM

The ornamental design for a combined tumbler and
toothbrush holder, substantially as shown and de-
scribed.

DESCRIPTION

FIG. 1 is a front perspective view of a combined tum-
bler and toothbrush holder showing my new design;
FIG. 2 is a front elevational view thereof, the rear being
unornamented;

FIG. 3 is a top plan view thereof, the bottom being
unornamented;

FIG. 4 is a right side elevational view thereof.
